UNITED STATES PATENT OFFICE.

ARTHUR EICHBERG AND HANS DIETZ, OF CHICAGO, ILLINOIS.

FOOTGEAR-FORMING MACHINE.

Application filed September 17, 1926. Serial No. 136,102.

The invention relates broadly to a foot gear forming machine.

An object of the invention is to provide a machine for stretching and forming foot gear that is inexpensive of manufacture, simple of operation and capable of efficiently performing the functions for which it is designed and is particularly adapted to use in the manufacture of one piece foot gear.

Another object of the invention is to construct a simple machine of this class in which is provided stretching elements arranged to carry a boot, shoe or other foot gear, constructed to exert any desired amount of pressure thereto, whereby the foot gear is formed and stretched into the desired shape without any cracking, splitting or injuring of the leather, or other material from which it is made and at the same time producing a neat, practical and highly commercial article for foot wear.

Another object of the invention is to provide a machine of the type that can readily be constructed as a multiple of units in one frame or as a number of separate units arranged one above the other or adjacent each other and capable of being conveniently operated by one or several separate sources of power.

Another object of the invention is to provide in a machine of this kind a driving mechanism of the self locking type such as a worm transmission, that will substantially automatically lock upon the stopping of the motor, thereby preventing an over-stretching or injuring of the article of foot wear that is being formed thereon.

Another object of the invention is to provide an automatic circuit breaking device in the machine that can be set to stop motor as the stretching elements reach any predetermined point, thereby preventing the stretching elements from traveling beyond the desired point by the force of the stored up energy in the moving parts of the machine.

Another object of the invention is to provide adjustable means for engaging the outer surface of the boot to insure its taking a proper configuration.

With the foregoing and such other objects in view as will appear as the description proceeds, the invention resides in the combination and arrangement of parts and in the details of construction hereinafter described

and claimed, it being understood that changes in the precise embodiment herein described, may be made within the scope of what is claimed without departing from the spirit of the invention.

60

In the drawings:

Figure 1 is a rear elevation showing the drive side of the machine, disclosed as a plurality stage type, with the duplicate operating mechanisms assembled as a unit between 65 a single set of frames.

Figure 2 is an end elevation viewed in the direction of the arrows indicated in Figure 1, at line 2—2.

Figure 3 is a transverse sectional view 70 shown on an enlarged scale taken on line 3—3 of Figure 1.

Figure 4 is a fragmentary transverse sectional view taken on line 4—4 of Figure 1 drawn on an enlarged scale.

75

Figure 5 is a fragmentary vertical sectional view taken on line 5—5 of Figure 2 drawn at an enlarged scale.

Figure 6 is a perspective view of one of the sections of one of the pairs of sliding elements shown connected to the uprights.

The frame proper comprises a pair of standards or side frames 11 and 12 secured to a base plate 13, by means of bolts or studs 14 extending through flanges 15 provided at 85 the bottom end of said side frames.

The standards are also provided with a plurality of horizontally aligned bosses 16 through which tie rods 17 extend to secure said standards together, said side frames 90 being held in spaced relation to each other against the tension of the tie rods 17 by spacer tubes 18 disposed over said tie rods.

Brackets 19 extend outwardly from the rear sides of the standards 11 and 12 at spaced intervals and are secured to finished bosses cast on said frames to hold said standards rigidly in place for mounting operating means, for parts to be hereinafter described.

Grooves 21—21 are cut in the standards 11 100 and 12 in horizontal alignment with each other to receive sliding elements. These sliding elements, as best illustrated in Figure 6, are each formed of an angle iron having its ends 22 bent inwardly at right angles thereto 105 substantially parallel to each other, and notched as at 23 to receive stretching elements. The ends or legs 22 are adapted to slidably fit into the grooves 21—21 of the side frames 11 and 12.

110

- The vertically aligned sections of the pairs of sliding elements are secured together, one series of sections by uprights 24 and the other series of superposed sections by uprights 24^a.
 5 Channels 25 and 25^a are secured one to each pair of spaced uprights 24 and 24^a in any convenient manner, substantially in the same horizontal plane, and are provided with nuts 26 and 26^a, the nuts 26 being split for assembling and of opposite hand to the nuts 26^a mounted on the opposite channel 25^a. The shafts 27 each have a right hand thread cut on its end 28 and a left hand thread cut on its end 28^a. These shafts extend through the solid nuts 26^a and the split nuts 26 into bearings 31 formed on brackets 19. A collar 32 is secured on each of the shafts 27 to abut the inner side of the bracket bearings 31 to prevent axial displacement in one direction, and 20 worm gears 33 secured to each shaft on the opposite side of the bearings 31 to prevent axial displacement in the opposite direction and to form means for engaging the driving means provided for the machine.
 25 Pairs of lugs 34 are cast integral with the brackets 19 and are bored in vertical alignment with each other to rotatably receive a vertical shaft 35 which has secured to it, worms 36 arranged to be disposed between the pairs of lugs 34, and placed to mesh with the worm gears 33. This shaft 35 is directly connected to a motor 37, mounted on the base 13.
 30 Pairs of stretching elements comprising sections 38 and 39 are preferably formed of flat material having their ends 41 and 42 directed at substantially right angles thereto and parallel with each other and then parallelly outwardly as at 43 and 44, substantially parallel to the main portions 38 and 39 of said stretcher elements. These stretcher elements are arranged to fit in the notches 23 in the sliding elements so that as said sliding elements are either forced apart or drawn together, they transmit a similar movement to the stretcher elements 38 and 39.
 35 Connected to each of these stretcher elements is a complementary section of a divided form comprising sections 45 and 46 which are adapted to carry a leather covering 47 from which the foot gear is made which will also be forced inwardly or outwardly as the sliding elements are forced inward or outward. A frame 49 of substantially the shape of the outer side of the boot or shoe 47 is secured to the stretcher element section 39, and carries thumb screws 51 spaced therein and arranged to engage a contour plate 52 arranged to engage the leather 47 of the foot gear lying between the form 46 and the contour plate 52.
 40 An electrical snap switch 53 is secured to the bracket 19 which will be engaged by one of the angles 24 as it reaches a predetermined distance, thereby breaking the circuit at a
 45 predetermined distance of travel, and stopping the motor. It will be seen that the switch 53 is mounted on an adjustable bracket 54 provided with slots 55 through which it is adjustably secured to the bracket 19 by machine screws or the like, so that it may be moved inwardly or outwardly to regulate and predetermine the point at which the current will be shut off and the machine stopped.
 50 The operation of the machine is substantially as follows: The divided forms are inserted inside of the leather, formed substantially to the shape of a boot or other foot gear, which has previously been soaked in a liquid, then the wedges 56 are forced between the stretching elements 39 to hold the section of the form rigid. The contour plate 52 is next put in place along the boot and the thumb screws 51 adjusted to hold the leather of the front part of the boot in contact with the form on the side 46, or contour plates may be provided for both sides of the boot if desired.
 55 The stretching elements 38 and 39 are next inserted in the notches 23 of the sliding elements, the machine is then ready for the stretching operation. The current is turned on starting the motor which rotates the shaft 35 in one direction, which causes the sliding elements to separate through right and left hand thread on the shafts 27 until the circuit is broken by the contact of one of the angles 24 with the electrical switch 53, whereupon the motor will stop, and the worm drive will lock the machine in this position, where it is allowed to stand until the foot gear, or boot is properly formed and dried; after which the motor is reversed by the hand switch 57, causing the sliding elements to move toward each other until released. Another switch 58 may be provided to automatically stop the motor after the sliding elements have moved toward each other a sufficient distance or the switch 57 may be thrown out by hand.
 60 The stretcher elements are then removed from the machine and the wedges 56 removed from between the complementary sections of the divided form and the boot removed, the machine is then ready to repeat the cycle.

We claim:

1. In a machine of the class described, a pair of side frames having aligned grooves in their inner sides, aligned elements slidably mounted therein, stretching elements operatively associated with said sliding elements, a form carried by said stretching elements and means for operating said sliding elements whereby said form is expanded.
2. In a machine of the class described, side frames having aligned grooves in their inner sides, aligned elements slidably mounted therein, stretching elements operatively associated with said sliding elements, a divided form carried by said stretching elements and means for operating said sliding elements.

whereby a spreading of the sections of the divided form takes place.

3. In a machine of the class described, a frame, aligned elements slidably mounted therein, stretching elements operated by said aligned elements, a form carried by said stretching elements adapted to carry a foot covering, means for adjustably engaging the outer surface of said foot covering to bring said covering in contact with the outer periphery of said form and means for operating said sliding elements whereby said form is caused to exert an expanding pressure on said foot covering.

4. In a machine of the class described, a frame, aligned elements slidably mounted therein, a divided form, a stretching element secured to the adjacent inner side of each section of said form and detachably connected to said sliding elements, and means for reciprocating the latter elements whereby a corresponding movement is transmitted to the sections of the form.

5. In a machine of the class described adapted to form foot gear, a longitudinally divided form, stretching elements secured to the adjacent longitudinal edges of the sections of said form, spacer elements between said stretching elements, sliding elements suitably mounted in a frame and detachably connected to said stretching elements and means for reciprocating said sliding elements whereby a corresponding movement is transmitted to said form sections.

6. In a machine of the class described, side frames mounted on a base, cross braces securing said side frames, a plurality of said braces having a journal therein, a plurality of pairs of sliding elements mounted in said side frames, members connecting the vertically aligned complementary sections of the pairs of sliding elements, a shaft having threads of opposite hand on their respective ends journaled in a plurality of said cross braces and means for driving said shafts whereby a correspondent movement is transmitted to said sliding elements.

7. In a machine of the class described, side frames mounted on a base, a plurality of cross braces each provided with a journal securing said frames, a plurality of pairs of sliding elements mounted in said side frames, stretching elements adapted to operate forms operatively associated with said sliding elements, uprights connecting the vertically aligned sections of the pairs of sliding elements, a right and left hand nut on each pair of sections of the pairs of uprights, shafts having

a portion threaded right hand and a portion threaded left hand journaled in said brackets arranged to engage said nuts and means for rotating said shafts whereupon said forms are caused to expand or contract depending upon the direction of rotation of said shafts.

8. In a machine of the class described, side frames mounted on a base, cross braces securing said frames, a plurality of said braces being provided with journals, a plurality of pairs of sliding elements mounted in said side frames, stretching elements adapted to operate forms operatively associated with said sliding elements, uprights connecting the vertically aligned sections of the pairs of sliding elements, a right and left hand nut on each section of the pairs of uprights, shafts having a portion threaded right hand and a portion threaded left hand mounted in aforementioned journals arranged to engage said nuts, worm gears secured to the ends of said shafts abutting said journals preventing displacement of the shafts in one direction, means for preventing displacement of said shafts in the opposite direction, worms arranged to drive said worm gears and means for driving said worms.

9. In a machine of the class described, a frame, aligned elements slidably mounted therein, stretching elements operated by said aligned elements, means for operating said sliding elements and means for automatically stopping and locking the device at a predetermined point.

10. In a machine of the class described, a frame, aligned elements slidably mounted therein, a divided form, stretching elements operatively associated with said form and aligned sliding elements, a worm drive and means for automatically breaking an electrical circuit whereby the machine is stopped and automatically locked against further rotation.

11. In a machine of the class described, a frame, aligned elements slidably mounted therein, a divided form, stretching elements operatively associated with said form and aligned sliding elements, a worm drive and means for driving said machine, means for automatically breaking an electrical circuit whereby the machine is stopped and automatically locked and means for reversing the direction of rotation of said machine.

In testimony whereof we affix our signatures at 10 South LaSalle St., Chicago, Illinois.
